BATHTUB MOUNTING

Dwight La Barre, Detroit, Mich., assignor to Borg-Warner Corporation, Chicago, Ill., a corporation of Illinois

Application April 26, 1947, Serial No. 744,269

4 Claims. (Cl. 4—173)

1

The present invention relates to bathtubs, basins, and like structures, and has particular reference to novel means for mounting and supporting a tub or the like on a wall structure.

It is one of the primary objects of this invention to simplify the construction of mounting devices for bathtubs and the like, and to improve the efficiency of such mounting devices.

Another principal object of the present invention resides in providing a novel arrangement for mounting a tub rim to a wall structure, such devices being adapted to prevent shifting movement of the tub away from the wall structure after being installed.

A further principal object is to provide tub mounting devices which are adapted to effect a seal between the tub rim, said mounting device and the wall structure.

Still another object resides in providing tub mounting devices which have means for effecting a key or tie-in between the same and the plaster or other finishing material of the wall structure, the arrangement being such that a portion of the mounting device lies in approximately the outer plane of the wall where it presents an ornamental bead.

Also it is an object of the present invention to provide mounting devices for bathtubs and the like which are so constructed and arranged that the labor usually required for mounting the tub is reduced to a few simple operations.

Other objects, aims and advantages of the invention contemplated herein will be apparent to persons skilled in the art after the construction and operation of the mounting devices is understood from the within description. It is preferred to accomplish the numerous objects hereof and to practice the invention substantially in the manner hereinafter fully described and as more particularly pointed out in the appended claims, reference being made to the accompanying drawings forming a part of this specification.

In the drawings:

Fig. 1 is a vertical transverse section, showing the improved mounting devices applied to a bathtub or the like;

Fig. 2 is a vertical elevation of a longitudinal portion of the structure shown in Fig. 1 with regions broken away for the purpose of clearness;

Fig. 3 is a detail in section showing a portion of the mounting devices prior to final assembly; and

Fig. 4 is a sectional view showing a slightly modified arrangement of the structure contemplated herein.

2

The drawings are to be understood as being more or less of a diagrammatical character for the purpose of disclosing typical or preferred forms of the invention contemplated herein. In the drawings like reference characters identify the same parts in the different views.

Referring first to Fig. 1 the tub body 5 has an outwardly flared rim portion 6 at the margin of which there is an upstanding lip 7. Secured to the under surface of rim 6 is an angle metal strip having a horizontal flange 8, welded or otherwise attached to the rim, and a down-turned flange 9 depending from the rim.

The wall structure may comprise vertical studs 10 which carry a bridge piece 11 and secured along the adjacent edges of the studs 10 are the laths 12 to which the plaster 13 is applied. The plaster may have an outer finishing coating 14 of any suitable material which is secured in position in any well-known manner.

For the purpose of supporting the tub rim 6 there are a plurality of horizontally spaced clips, identified generally as 15, which may be metal stampings or the like. For the purpose of simplicity one clip will be described in detail. The clip has a flat body portion 16 which lies flat against the adjacent surface of the bridging 11 and is apertured to receive the attaching screw 17 which is threaded into the bridging 11 in the manner shown in Fig. 1. Above the flat body portion 16 the clip has a portion 17 offset away from the plane of said body portion and at its upper margin is flared outwardly as at 18. In order to mount the tub on the clips 15, said tub is raised until the depending flange 9 can be inserted into the space between the offset portions 17 of the clips and the adjoining bridging surface. This arrangement effectively supports the tub body and also prevents its movement in a direction away from the wall structure upon which it is mounted.

As before stated, means are provided in connection with the mounting devices for sealing adjacent portions of the tub rim and the wall structure. The sealing means, in the present instance take the form of an elongated strip identified generally as 19. A longitudinal region of the sealing strip has in it a reverse or hair pin bend 20 to define a flat back member 21 which is placed flat against the bridging 11 as seen in Fig. 1. The hair-pin bend 20 will be positioned uppermost when the strip is secured to the wall structure. Pendent from bend 20 is a spring member 22 which is in a plane oblique to the plane of the

back member or flange 21 and has an ogee or S-shaped bend 23 intermediate its upper and lower margins and then continues downwardly to provide a narrow flat region 24. Thus a longitudinal groove is provided which extends the length of the strip. The upturned lip 7 of the tub rim will be positioned between the members 21 and 22 defined by the hair-pin bend and these members are apertured to receive the screws 25 which are inserted therethrough and threaded into the bridging 11 for anchoring the strip on the wall structure.

Below or beyond the narrow flat region 24 of oblique member 22, there is an outward flange 26 extending away from lip 7 to overlie the tub rim 6 in spaced relation thereto. This spacing of the parts provides a longitudinal channel 27 above the tub rim into which suitable sealing material 28 is inserted in a plastic state. The strip above described, prior to being mounted on the bridging 11 has its members 21 and 22 yieldably spaced apart a proper distance, as shown in Fig. 3, to permit the sealing material being readily inserted in the channel 27 and also to receive the lip 7 of the tub rim. It will be understood that these parts are assembled and mounted on the wall structure before the plaster or the like is applied. When the screw 25 is being tightened into place, the members 21 and 22 will move towards each other until the narrow flat region 24 firmly contacts the lip 7 and at the same time the sealing material 28 will be compressed by flange 26.

The end region of the outward flange 26 is bent back upon itself as at 29 which provides a small bead-like edge which may be plated or otherwise treated to give an artistic finish to the arrangement. At the inner edge of the bent back portion there are upstanding means which may take the form of a plurality of suitably shaped lugs or ears 30 as seen in Fig. 2 or may be a continuous rib 30a as shown in Fig. 4. In either event these upstanding means 30 or 30a are in a plane intermediate the planes of the inner and outer surfaces of the plaster 13 or other finishing material of the wall structure. Thus, when the plaster or finishing material is applied to the framework of the wall, such material will be forced into the groove at flat portion 24 back of ears 30 or rib 30a so that said ears or rib will provide a key or tie-in for the plaster, as will be understood.

In lieu of using the arrangement above-described for supporting the tub by means of the clips 15 and down-turned rim flange 9, these members may be omitted and the tub may be supported by suitable blocking 31 shown in Fig. 4. The blocking 31 may be a continuous wood strip or several pieces of wood strip which are nailed or otherwise secured to the bridging 11 and studs 5. The top surface of the blocking 31 is horizontal adjacent the bridging as shown at 32 to engage the margin of rim 6, and the forward portion thereof is chamfered as at 33 to extend under the curved portion of tub rim 6 with its corner 34 engaged therewith in the manner shown.

While this invention has been described in its preferred forms or embodiments, it will be apparent to persons skilled in the art after understanding the improvements, that various changes and modifications may be made therein without departing from the spirit or scope thereof. It is aimed in the appended claims to cover all such changes and modifications.

What is claimed is:

1. A tub, basin, and the like, having a lateral rim extending longitudinally along the upper portion thereof adjoining a wall structure; means on said wall structure for supporting the tub; and an upstanding longitudinal lip along the margin of said rim adjacent the wall structure; in combination with expansion means secured to said wall structure and extending horizontally alongside said tub lip, said expansion means comprising a sheet metal strip formed with an elongate inverted V-shaped hair-pin bend defining longitudinally extending back and front sections between which said lip is received, said longitudinal back section being arranged against said wall structure, and said longitudinal front section being adapted to flex with respect to said back section and having a free lower margin; a longitudinal lateral flange extending along the free lower margin of said front section in spaced relation above said tub rim, said flange and rim together defining a longitudinal channel; sealing material in said channel; and attaching means passed through said back and front sections for securing said expansion means to said wall structure, said attaching means being adapted to bodily flex said front section towards said back section to clamp said lip between said sections and to press said sealing material against said tub rim.

2. An arrangement as defined in claim 1, wherein the wall structure includes outer facing material back of which the expansion strip is positioned; and the longitudinal lateral flange of the expansion strip has upwardly extending means imbedded in the outer facing material of the wall structure.

3. A tub, basin, and the like, having a lateral rim extending longitudinally along the upper portion thereof adjoining a wall structure; means on said wall structure for supporting the tub; and an upturned longitudinal lip along the margin of said rim adjacent the wall structure; in combination with expansion means secured to said wall structure and extending horizontally alongside said tub lip, said expansion means comprising a sheet metal strip which is separate from and is spaced above said supporting means, said sheet metal strip being formed with an elongate inverted V-shaped hair-pin bend defining longitudinally extending back and front sections between which said lip is received, said longitudinal back section being positioned between said upturned lip and said wall structure, and said longitudinal front section being in a plane oblique to the plane of said back section and being adapted to flex with respect to said back section; an outwardly extending longitudinal flange along the lower margin of said front section in spaced relation above said tub rim, and the outer region of said flange being bent inwardly upon itself to provide a longitudinal bead above the tub rim, said flange and rim together defining a longitudinal channel; sealing material in said channel; and attaching means passed through said back and front sections for securing said expansion means to said wall structure, said attaching means being adapted to bodily flex said front section towards said back section to clamp said lip between said sections and to press said sealing material against said tub rim below said bead.

4. A tub, basin, and the like, having a lateral rim extending longitudinally along the upper portion thereof adjoining a wall structure; outer facing material on said wall structure and an up-

standing longitudinal lip extending along the margin of said rim adjacent the wall structure; means upon said wall structure for supporting the tub; and an elongate sheet metal strip formed with a longitudinal inverted V-shaped hair-pin bend defining longitudinally extending back and front sections of approximately the length of said rim and lip and between which said lip is received, said longitudinal back section contacting said wall structure, and said longitudinal front section being flexible; a longitudinal lateral flange extending outwardly along the lower margin of said front section to overlie said tub rim in front of said lip and with said rim defining a longitudinal channel; sealing material in said channel; attaching means passed through said back and front sections for securing said expansion means to said wall structure, said attaching means being adapted to bodily flex said front section towards said back section to clamp said lip between said sections and to press said sealing material into sealing engagement with said tub rim; the

outer region of said longitudinal flange having a bent back portion defining at its outer edge a longitudinal bead at approximately the plane of the outer surface of said wall facing material; and upstanding rib means intermediate the inner edge and the bead edge of the said longitudinal flange, said rivet means being embedded in said facing material of the wall structure.

DWIGHT LA BARRE.
